UNITED STATES PATENT OFFICE.

WILLIAM A. V. PORTER, OF NEW YORK, N. Y., ASSIGNOR TO DAVID WEIL'S SONS LITHOGRAPHIC COMPANY, OF BROOKLYN, NEW YORK, A CORPORATION OF NEW YORK.

COLLAPSIBLE DISPLAY-CARTON.

1,202,422.

Specification of Letters Patent. Patented Oct. 24, 1916.

Application filed August 26, 1915. Serial No. 47,495.

To all whom it may concern:

Be it known that I, WILLIAM A. V. PORTER, a citizen of the United States, and resident of the borough of Manhattan, in the 5 city and State of New York, have invented a new and useful Improvement in Collapsible Display-Cartons, of which the following is a specification.

This invention relates to a collapsible display carton, with the object in view of providing an article of this character which may be cut from sheet material in the form of a blank, at one operation, with economy of material; and which may be readily folded into a strong and serviceable carton having numerous smooth display surfaces, and having a novel arrangement for supporting the cover in open position in which its inner surface may be used as a display surface.

20 A further object is to provide such an article in which the blank from which it is folded is so formed that the outer surfaces of the front, back, and ends, and the inner surface of the cover, all of which surfaces 25 may be used for the purpose of display, are on one side of the blank when in flat form.

A still further object is to provide certain improvements in the form and arrangement of the several parts whereby the above 30 named and other objects may be effectively carried out.

A practical embodiment of my invention is represented in the accompanying drawings, in which,

35 Figure 1 represents a plan view of the blank from which the carton may be folded. Fig. 2 represents a top plan view of the folded carton with the cover closed. Fig. 3 represents a similar view with the cover 40 open and supported in open position. Fig. 4 represents an end view of the parts shown in Fig. 3. Fig. 5 represents a section taken in the plane of the line A—A of Fig. 3, looking in the direction of the arrows, and 45 Fig. 6 represents a section taken in the plane of the line B—B of Fig. 3, looking in the direction of the arrows.

The material from which the carton is to be made may be any suitable sheet material, 50 but I preferably employ cardboard of a quality and character which is familiar to those in this art. This sheet material may be laid out flat and stamped out at one blow with a die, or suitably stamped out or cut in 55 any well known or approved manner. At

the same time that the blank is stamped or cut out, it may also preferably be creased, in a well understood manner, along the lines where folding is to take place in the formation of the box or carton.

The form of blank which embodies the subject-matter of this representation is clearly shown in Fig. 1, and comprises various panels, flaps, ears, and slits, all of which combine and coöperate in the constitution of the formed carton. The panel which constitutes the back of the box is denoted by 1; the panel which constitutes the front by 2; the panels which constitute the ends by 3, 4; the panel which constitutes the bottom by 5; and the panel which constitutes the cover by 6. These panels are shaped in the present instance, so as to constitute a box which is substantially square in plan view and two and one-half times as wide and deep as it is high. However, it will be understood that the particular proportions are not essential of the invention. The panels 1, 2, designed to form the back and front of the carton respectively, are provided at their ends with wings 7, 8 and 9, 10, respectively, which wings are designed to be bent inwardly when the blank is being folded and lie along the ends of the carton. These wings are shown of such size and shape that, when they are folded as described, they substantially close the ends of the box or carton, i. e. the said wings are substantially the same width as the height of the sides of the carton, and the extremities of the wings, 7, 8 and 9, 10, substantially abut when in said position.

The panel 5, which forms the bottom of the article, has panels 11, 12, which project from its sides and which are of substantially the same size and shape as the panels 3, 4, which form the ends or sides of the carton. These panels 11, 12, are, however, slightly narrower than the panels 3, 4, and they are calculated to fold upwardly from the bottom panel 5, along the ends of the box between the in-turned wings 7, 8, 9, 10, and end panels 3, 4, thus serving as reinforcing elements for the end portions. Slits 13, 14, are fashioned at the juncture of the panels 11, 12; and the panel 5, which slits are so arranged and of such a size as to be fitted to snugly receive ears 15, 16, which protrude from the sides of the end panels 3, 4, respectively; the said coöoperative engage-

ment of the slits and ears insuring the retention of the various parts constituting and reinforcing the ends of the carton, as described, in folded position.

5 The back panel 1 has a narrow lip 17 extending substantially throughout its width and located at the edge thereof, which lip is intended to be provided with an adhesive so that it may be secured to the outside of 10 the cover panel 6, near its line of juncture with the end panels 3, 4, so as to hold the front, back and bottom of the carton in folded shape. It will be understood that this adhesive may be applied either prior to or 15 during the folding of the blank and that it may be applied either to the lip 17, as suggested, or to the portion of the cover panel 6 which the said lip contacts, as described.

The cover panel 6 is connected with the 20 end panels 3, 4, by means of corner pieces 18, 19; and the said end panels are also provided with inwardly projecting supporting flaps 20, 21. These supporting flaps are designed to be folded upwardly, and are provided at their extremities with ears 22, 23, adapted to engage slits 24, 25, cut into the cover panel 6; this interengagement of the said ears and slits serving to hold the cover in open position substantially at right angles 25 to the plane of the top of the box. By cutting the blank so that these supporting flaps 20, 21, are attached to the end panels 3, 4, and removably engage the cover panel 6, rather than the opposite arrangement, I am 30 able to effect two important results: first, there is economy of material in that the portion of the blank which would be removed in order to leave the top of the box open, is partially utilized to form the supporting 35 flaps; and, second, the fact that these flaps are not attached to the sides of the cover panel 6, enables the adjacent blanks cut from the sheet material to "interlock" as said in this industry, that is, the material of 40 one blank to project into or overlap the material of the adjacent blank, thereby effecting a considerable saving of material. A further object of this arrangement lies in the fact that these supporting flaps fold 45 down flat underneath the cover when the carton is closed, thereby avoiding any tendency to bulge.

In order to receive the ears 22, 23, when 50 the flaps are thus folded, I cut away a portion of the cover panel 6, as indicated at 26. To secure the front panel 2 to the end panels 3, 4, and thus have the blank remain in a single piece, I provide a flange or edge 27. This may be of such size and shape as to 55 ornament the edges of the opening in the top of the box, and it also serves the purpose of preventing articles from falling out in case the carton is placed at an angle to the horizontal.

60 65 In folding the carton from the blank, as

shown in Fig. 1, the following steps are taken, to wit: The back panel 1 is folded at right angles to the bottom panel 5; the bottom panel 5 is folded at right angles to the front panel 2; the front panel 2 is folded at right angles to the flange 27 and end panels 3, 4; the lip 17 is then glued or otherwise caused to adhere to the back of the panel 6, as described, and clearly shown in Figs. 4 and 5. Next, the wings 7, 8, 9, 10, are folded at right angles to the panels 1, 2; the reinforcing panels 11, 12 are folded at right angles to the bottom panel 5, so as to lie over the wings 7, 8, 9, 10; the end panels 3, 4, are folded at right angles to the corner pieces 18, 19, flaps 20, 21 and flange 27, so as to overlie the panels 11, 12; and finally, the ears 15, 16, are caused to enter the slits 13, 14. The box is now folded or completely shaped and may either be closed by 70 folding down the cover panel 6, or the latter may be folded up at right angles and supported in such position by the flaps 20, 21, when they are bent upwardly and their ears 75 22, 23, caused to engage the slits 24, 25. 80

From the foregoing, it will be observed that I not only provide a blank which is fitted to form a strong and serviceable carton, but the blank is so arranged and divided that those parts which constitute the outside of the body of the carton when folded, and the inside of the cover, are all on one side of the blank. Hence, all the surfaces which are designed and adapted to be used as display surfaces may be printed with the appropriate subject-matter at one operation and without reversing the blank. 90

95 It will be understood that various changes may be resorted to in the form and arrangement and material without departing from the spirit and scope of my invention, and hence I do not intend to be limited to specific details herein shown and described except as they may be set forth in the claims. 100

105 What I claim is:

110 115 120 125 130 135 1 A carton of the character described, comprising a blank of sheet material cut to shape and adapted to be folded into box formation, said blank having panels designed to constitute the front and back of the folded box, panels designed to constitute the ends of the folded box, a panel designed to constitute the bottom of the folded box, wings located at the ends of the said front and back panels and adapted to fold along the ends of the box, and reinforcing panels located at the sides of the bottom panel and adapted to fold between the said wings and the end panels, the said end panels having ears and the said reinforcing panels having slits adapted to receive said ears for holding the said wings, reinforcing panels and end forming panels in folded position.

2. A carton of the character described,

comprising a blank of sheet material cut to shape and adapted to be folded into box formation, said blank having panels designed to constitute the ends of the folded box, a panel designed to constitute the cover of the box and fitted when open to act as a display surface, and supporting flaps, both the cover panel and the said flaps being attached to the end forming panels and having coöoperating slits and ears, whereby the flaps may hold the cover open and in display position.

3. A carton of the character described, comprising a blank of sheet material cut to shape and adapted to be folded into box formation, said blank having panels designed to constitute the ends of the folded box, a panel designed to constitute the cover of the box and fitted when open to act as a display surface, and supporting flaps, both the cover panel and the said flaps being attached to the end forming panels, said flaps having ears and

the cover panel having slits designed to receive said ears, whereby the flaps may hold the cover open and in display position.

4. A carton of the character described, comprising a blank of sheet material cut to shape and adapted to be folded into box formation, said blank having panels designed to constitute the ends of the folded box, a panel designed to constitute the cover of the box and fitted when open to act as a display surface, and supporting flaps, both the cover panel and the said flaps being attached to the end forming panels and having coöoperating slits and ears, whereby the flaps may hold the cover open and in display position and may be folded inwardly and be covered by the cover panel when the carton is closed.

In testimony, that I claim the foregoing as my invention, I have signed my name this seventeenth day of July 1915.

WILLIAM A. V. PORTER.
